UNITED STATES PATENT OFFICE

JOHAN E. JOHANNESEN, OF BROOKLYN, NEW YORK

OVERALLS

Application filed September 12, 1930. Serial No. 481,540.

This invention relates to improvements in garments, and has more particular relation to workmen's garments generally referred to as "overalls."

5 The object of the invention is to provide a garment which may be instantly adjusted to be slipped on or off, and to have different portions of it adjustable after it is on, and at the same time to provide a garment of pleasing appearance.

Another object of the invention is to provide a garment of the character specified that is secured by the so-called slide fasteners so that it will not accidentally become unfastened by the exertions of the workman.

The invention consists in cutting the trouser and body sections with an open seam along the side from the side pocket line to the neck, and securing this open seam by the two members of a slide fastener, this fastener being concealed when in its closed condition.

The invention further consists of a garment having a slide fastener secured opening along the front body portion so that it may be put on, and a slide fastener secured seat portion with protecting flaps for concealing the slide fasteners.

The invention consists further of other structures, all of which will be hereinafter more particularly set forth and claimed.

In the accompanying drawings forming part of this specification:

Figure 1 represents a side elevation of a garment embodying the present invention in use.

Figure 2 represents a rear elevation of the same.

Figure 3 represents a broken rear elevation with the seat portion open.

Figure 4 represents a front elevation of a modified form of the garment intended for a young boy, and

Figure 5 represents a broken rear elevation of the garment shown in Figure 4.

Described in general terms, the invention consists of a sleeveless overall made of suitable material and constructed so that it may be put on by an open seam along one side of the body portion, this seam being secured by

the so-called slide fastener with a protecting and concealing flap over it.

The trouser portion of the garment, which is in one with the body or waist portion, is provided as shown in Figure 3, with a triangular flap at the rear, this flap being provided along its fastening edges with slide fastener elements, and the companion slide fastener element being attached to the main portion of the trouser, suitable protecting flaps for the slide connectors and for the slide fastener being provided to conceal them when the garment is in use.

Described in detail, 1 represents the front of the body section 29. This, as best shown in Figure 1, is open as at 30 from the V-neck to the point 27 below the waist band on the side of the trouser, so that the garment may be opened along this line. This opening permits the workman to step into the trouser portion 28, and then place his arms through the sleeveless armholes 29.

One member of the slide fastener 2 is secured to one section of the front, while the remaining member of the slide fastener is secured along the edge of the companion member of the front by sewing or otherwise. This slide fastener is of an ordinary well-known construction comprising two metallic hook members which are pulled into interlocking relation by slide fasteners 11 and 12 such as shown in Figure 3. As this fastener is old and well known in the art, no further description of it is thought to be necessary.

As one member of the slide attachment at this point is applied on the underside of the upper body portion, it, of course, will be concealed when the slide fastener is drawn to its upper end to pull the two parts together. A snap fastener is attached to the two meeting portions at 19 so as to additionally fasten the front member down over the slide fastener and conceal the latter.

The usual breast pocket 31 is attached to the front of the body portion as shown in Figure 1.

The trouser portion of the garment is formed in the usual manner with the exception that at the rear, as shown in Figure 3, a triangular flap is arranged, having slide

members 14. These slide members coact with companion slide members 4 secured to interior flaps 7 and 8 so that when the slide fasteners 11 and 12 are drawn upward, the 5 triangular portion 13 will be secured firmly against the flaps 7 and 8 and form the seat of the trouser. This structure binds the flap 13 to the flaps 7 and 8 at a point slightly distant from the edge of the body portion of the trouser or opening so that when the slide 10 fasteners are both drawn as above described to lock the seat in position, the edges 3 and 5 of the trouser proper will project over the slide fastener and completely conceal it as 15 shown, more clearly in Figure 2. To hold the flaps 3 and 5 down closely in contact with the trouser proper, the edges of the flaps are provided with snap fasteners 9 and 10 which snap into suitable companion fasteners attached to the flap 13. The rear parts of the 20 portions 3 and 5 are provided with hip pockets 20 and 21 having buttoned flaps.

As the slide fasteners 11 and 12 might cause the flaps 3 and 5 to bulge and project 25 and be unsightly, I provide a curved flap 17 secured at its upper edge to the waist band 16 and having a glove fastener 18 arranged to co-act with a companion fastener 15 arranged on the flap 13. By this means, the 30 flap 17 is secured down firmly in position over any unsightly bulge or any portion of the fasteners 11 and 12 that may project beyond the flaps 3 and 5, and a neat and finished appearance given to the rear of the trousers.

The waist band 16 is loose at one end and formed with a button hole so that it may be secured over a button 32 secured to the opposite ends of the waist band, after the slide 40 fastener 2 has been secured. This assists in holding the front loose flap in position, as this flap projects to a point 27 below the waist line.

In the modified form of my improved garments shown in Figures 4 and 5, and which 45 is intended for the use of young boys as a playing overall, I form the short trousers as shown, and the rear of the trousers as in Figures 3 and 5. The upper or body portion, however, is divided on the line of the L-shaped band 24 so that the breast member 23 may be drawn over the shoulder from the rear, and buttoned down on the lower body member 34.

In this particular form of garment, the body portion 1 at the right is only extended 55 a short distance above the waist line 16 as at 34, and is provided with suitable snappers 35 for engagement with the snappers on the breast portion 23. On the left hand side, 60 however, the body portion extends up over the left shoulder and is formed in the front with the L shape band 24 which is provided with fasteners 35 engageable with similar fasteners on the breast portion 23. The slide fastener 2 in this instance extends from 65 the right edge of the breast portion 22 at the end of the L shape fastener band down past the waist band, the right hand side pocket and to a point well down the side seam of the trouser leg.

Pockets 25 are arranged just above the 70 waist band and are of the inside type, that is, the pocket itself is inside the overalls with the opening or flap on the outside. A suitable breast pocket 31 is sewed on to the breast section 22.

The remainder of the boy's overall and the trouser section is constructed substantially as shown in the men's overall in Figures 1, 2, and 3. The slide fasteners along the line 2 in this form of the invention are set substantially in the same manner as they are in the form shown in Figure 1 so that the outside flap will conceal the slide fastener underneath.

With the above construction, if it is desired to remove the overalls, the snappers on the angular band 24 are first opened, the slide fastener 2 then opened and the fasteners 35 on the band 24 then opened, which leaves the breast section 23 free to be thrown back over the shoulder when the boy can step out of the overall. In donning the garment, the reverse takes place, the breast section 23 being thrown over the right shoulder and secured to the section 34 and the left breast section 22 then secured in position and the slide fastener 2 closed.

It will be seen from the foregoing description that while these garments may be instantly put on or taken off, that after the slide fasteners are secured in position it is next to impossible for them to become accidentally unfastened.

Further, by the peculiar construction and arrangement of the parts, and particularly the rear of the trouser, the fasteners are completely concealed by their respective flaps, and the whole garment has a finished and neat appearance, in which the fastening or securing devices are covered in a way to conceal their presence entirely.

Anyone not being familiar with the garment, upon looking at it, would be puzzled to know just how it was secured in position upon the wearer, as all the fasteners are completely concealed.

A further advantage of the application of the slide fasteners and strips is that while these are completely concealed, they at the same time are kept out of contact with the clothing worn under the overall, and thus will not wear any shiny spots on the clothing or in any way damage it.

The construction also facilitates very rapid donning or putting off of the garment and very rapid adjustment of the different parts, as the slide fastener is of course one of the quickest known means of fastening flexible bodies together. These slide fasteners, because of their peculiar characteristics and

their flexible construction, also do not interfere in any way with the movements of the wearer, and he is not conscious at any time of a complete metallic fastening of the separate parts of the garment.

Further, the most strenuous efforts of a workman wearing this overall, cannot cause the fastener elements to accidentally separate, as the material of which the overalls are made would first tear before the fastener elements would let go their interlocking grip.

Applicant is of course aware that slide fasteners have been used for securing clothing in position, but the peculiar construction and arrangement by applicant of the slide fasteners strips with their underlying and overlapping flaps for completely concealing them without in any way interfering with their rapid operation, is believed to be entirely new.

It will, of course, be understood that as the principal parts of my present invention relate to the trouser portion of the garment that these trouser portions may if so desired be used without the upper body portion and as a trouser overall.

Having thus described my invention, what I claim is new and desire to secure by Letters Patent is:

In an overall, the combination with joined body and trouser portions, the latter being formed with a triangular seat flap with one apex at the waist line, of slide fastener strips applied along the meeting edges of the flap and trouser portions, flaps for covering the slide fastener strips along the edges of the triangular seat, and a horizontal curved flap secured to the waistband above the apex of the seat flap for covering the converging edges of the triangular seat, slide fastener strips and slide fasteners.

In testimony whereof I affix my signature.
JOHAN E. JOHANNESEN.
